UNITED STATES PATENT OFFICE.

JOHN HOLTZMAN, OF NEW YORK, N. Y., ASSIGNOR OF ONE-HALF TO JULIUS SARG, OF NEW YORK, N. Y.

SASH-HOLDER.

1,078,856.

Specification of Letters Patent.

Patented Nov. 18, 1913.

Application filed May 13, 1913. Serial No. 767,278.

To all whom it may concern:

Be it known that I, JOHN HOLTZMAN, a resident of the city of New York, in the county of New York and State of New York, have invented certain new and useful Improvements in Sash-Holders, of which the following is a specification.

This invention relates to sash locks for windows, and particularly to sash holders for the type of windows wherein an upper and a lower sash guided in ways are slideable upwardly and downwardly for opening and closing the window.

The principal object of my invention is to provide an improved window sash holder.

Another object is to provide means for positively maintaining the holder in locked state and prevent releasing thereof from the exterior of the apartment when the window is partially left open for ventilation.

A further object is to provide means for setting the holder in inoperative state for allowing the window sashes to open freely.

In carrying out the invention, an inclined base is secured to the lower sash and a roller cooperating with said base is wedged thereagainst by pressure of the upper sash against the periphery of said roller, where-

by movement of the sashes to open the window is automatically prevented. Said roller is mounted to rotate on a releasing lever which is slotted at its fulcrum to permit the roller to roll freely on said base. Actuating of said lever lifts said roller temporarily

to permit opening of the window. A tapped nut is pivotally secured to said lever and a screw threading therethrough is adaptable to be threaded against a fixed projec-

tion or into a threaded opening therein. Threading the screw against said projection positively maintains said roller in locked state, whereby tampering therewith from the exterior is prevented, and threading

said screw into said opening holds said roller lifted and positively maintains the lock in inoperative state.

Other objects and advantages will hereinafter appear.

In the accompanying drawings,—Figure 1 is a general side elevation of the window holder, showing its parts in the position when locking the window sashes. Fig. 2 is

a view similar to Fig. 1, and shows the position of the parts when the holder is released for opening the window. Fig. 3 is a view similar to Fig. 2, and shows the holder set to be maintained in inoperative state and the window sashes free to open. Fig. 4 is a front elevation of the holder as seen when its parts are in the position shown in Fig. 3.

The upper window sash 1 and the lower window sash 2 are suitably guided in ways and are counterweighted in the well known manner, whereby they may be shifted upwardly and downwardly to open and close the window. The holder is fixed on top of the lower sash 2, opposite the side of the frame of sash 1, by means of ears 3 depending from its base 4 being secured to sash 2 with wood screws 5. Said base comprises a rear wall 6, a wall 7 inclining downwardly from wall 6 toward the sash 1, and side walls 8 at each side of said inclined wall 7 and parallelly to each other. A roller 9, preferably provided with a rubber periphery 10, is adaptable to roll upwardly and downwardly along the inclined wall 7, and is guided laterally by the side walls 8. Any attempted movement to open either of said sashes, a downward movement of the upper sash or an upward movement of the lower sash, causes the roller 9 to be wedged between the inclined wall 7 and the side 1^a 85 of the sash, Fig. 1, whereby such relative movement of the sashes is normally prevented.

The roller 9 is rotatably mounted to run on a journal or bearing 11 which forms part of a releasing lever 12 fulcrumed on a stud 13 fixed to the wall 8 of casing 4, and said lever has a slot 14 at its fulcrum whereby the roller 9 is permitted to roll in contact with every portion of the inclined wall 7 while being fittingly mounted on its journal 11.

Pressure upon the extremity 15 of lever 12 lifts the roller 9 to the position shown in Fig. 2, which temporarily releases the roller and enables the window to be opened, by downward movement of the upper sash or upward movement of the lower sash, to any desired position. Upon releasing the pressure on said lever the roller 9 is restored to its normal position, Fig. 1, and automatically

locks the sashes, which precludes further movement of either sash in a direction to open the window, although the upper sash is free to be moved upwardly and the lower sash downwardly to close the window.

When the window is opened partially at night to permit ventilation of the apartment, it is desired to prevent burglars from tampering with the sash holder in order to open the window fully, who might press the lever 12 by reaching thereto with a rod or pull the roller 9 with a hook to render the holder inoperative. For this purpose a nut 16 is pivotally secured to the lever 12 adjacent its extremity 15, and a screw 17 threading therethrough is provided with a smooth round head 18 and a small lug 19 at its end. To prevent tampering with the lock to render it inoperative said screw is threaded downwardly to the position shown by the dot and dash lines, Fig. 1, and its lug 19 thereby caused to enter an opening 20 provided in a projection 21 extending from the casing 4, whereby actuating of said lever is prevented 25 and the roller is maintained in locked state. Threading the screw 17 back to the position shown restores the holder to normal action.

If it is desired to maintain the holder set in inoperative state to enable opening of the window freely, without requiring actuating of the releasing-lever 12, for such purpose as cleaning the window-panes, said lever is swung to the position shown in Fig. 3 to release the roller 9 and the screw 17 is caused 35 to thread within a tapped opening 22 provided in projection 21, which permanently holds said lever and roller in inoperative position. Threading back the screw 17 to the position shown in Fig. 1 restores the holder 40 to operative state.

Variations may be resorted to within the scope of the invention, and portions of the improvements may be used without others.

Having thus described my invention, I 45 claim:

1. In a window sash holder, the combination with a base on one of the sashes, and a roller adaptable to coöperate with said base to prevent relative movement of the sashes, of a lever for releasing said roller, a nut pivoted to said lever, a screw threading through said nut, a fixed member having an opening and a tapped opening, said screw adaptable to engage said opening to maintain said lever 50 to hold the roller in locked position, and said screw adaptable to thread within said tapped opening to maintain said lever to hold the roller in inoperative position.

2. In a window sash holder, the combination with a base on one of the sashes, and a roller adaptable to coöperate with said base to prevent relative movement of the sashes, of means to positively maintain said roller locked in inoperative state.

3. In a window sash holder, the combina-

tion with a base on one of the sashes, and a roller adaptable to coöperate with said base to prevent relative movement of the sashes, of a lever for releasing said roller, a nut pivoted to said lever, a screw threading through said nut, a fixed member having an opening, and said screw adaptable to engage said opening to maintain said lever set to hold the roller in locked position. 70

4. In a window sash holder, the combination with a base on one of the sashes, and a roller adaptable to coöperate with said base to prevent relative movement of the sashes, of a lever for releasing said roller, a nut pivoted to said lever, a screw threading through said nut, a fixed member having a tapped opening, and said screw adaptable to thread within said opening to lock said lever to maintain the roller set in inoperative position. 75

5. In a window sash holder, the combination with a base on one of the sashes, and a roller adaptable to coöperate with said base to prevent relative movement of the sashes, of a lever for releasing said roller, a nut pivoted to said lever, a screw threading through said nut, a fixed member, and said screw adaptable to engage said member to maintain said lever set to hold the roller in locked position. 80

6. In a window sash holder, the combination with a base on one of the sashes, and a roller adaptable to coöperate with said base to prevent relative movement of the sashes, of a lever for releasing said roller, a nut on said lever, a screw threading through said nut, a fixed member having a tapped opening, and said screw adaptable to thread within said opening to lock said lever to maintain the roller set in inoperative position. 100

7. In a window sash holder, the combination with a base on one of the sashes, and a roller adaptable to coöperate with said base to prevent relative movement of the sashes, of a lever for releasing said roller, a nut on said roller lever, a screw threading through said nut, a fixed member, and said screw being adaptable to engage said member to maintain said roller in locked position. 110

8. In a window sash holder, the combination with a base on one of the sashes, and a roller adaptable to coöperate with said base to prevent relative movement of the sashes, of a lever for releasing said roller, a tapped nut for said lever, and a screw engaging with said nut adaptable to lock said lever to maintain the roller set in inoperative state. 120

9. In a window sash holder, the combination with a base on one of the sashes, and a roller adaptable to coöperate with said base to prevent relative movement of the sashes, of a lever for releasing said roller, 125

a tapped nut for said roller lever, and a screw engaging with said nut adaptable to maintain said roller in locked state.

10. In a window sash holder, the combination with a base on one of the sashes, and a roller adaptable to coöperate with said base to prevent relative movement of the sashes, of a tapped nut, and a screw engaging with said nut adaptable to maintain 10 said roller set in inoperative state.

11. In a window sash holder, the combination with a base on one of said sashes, and a roller adaptable to coöperate with said base to prevent relative movement of the 15 sashes, of a tapped nut, and a screw engaging with said nut adaptable to maintain said roller set in inoperative state and to maintain said roller in locked state.

12. In a window sash holder, the combination with a base on one of the sashes, and a roller adaptable to coöperate with said base to prevent relative movement of the sashes, of a tapped nut, and a screw en- 20

gaging with said nut adaptable to maintain said roller in locked state.

13. In a window sash holder, the combination with a base on one of the sashes, and a roller adaptable to coöperate with said base to prevent relative movement of the sashes, of a lever for releasing said roller having a bearing, said roller mounted to run on said bearing, said lever being adaptable to shift longitudinally from its fulcrum to permit free engagement of said roller with said base, a tapped nut for said lever, and a screw engaging with said nut adaptable to lock said lever to maintain the roller set in inoperative position and to maintain said lever to hold the roller in locked state.

Signed at the city of New York, in the 40 county of New York, and State of New York, May, A. D. 1913.
